UNITED STATES PATENT OFFICE.

HENRY A. CARPENTER, OF SEWICKLEY, PENNSYLVANIA, ASSIGNOR TO RITER-CONLEY MANUFACTURING COMPANY, OF PITTSBURGH, PENNSYLVANIA, A CORPORATION OF NEW JERSEY.

RETORT-FURNACE.

1,150,808.

Specification of Letters Patent. Patented Aug. 17, 1915.

Application filed July 3, 1913. Serial No. 777,216.

To all whom it may concern:

Be it known that I, HENRY A. CARPENTER, a citizen of the United States, residing at Sewickley, in the county of Allegheny and State of Pennsylvania, have invented 5 certain new and useful Improvements in Retort-Furnaces, of which the following is a specification.

Heretofore, in the construction of benches 10 of retorts for gas-making apparatus, and also for coke ovens, and similar exteriorly-heated apparatus, it has been the practice to form the retorts as independent structures from the supporting walls, and ordinarily 15 of different materials and shapes, in which constructions the cross or vertical settings or supports have been placed at considerable distances apart.

An object of my invention is to provide a 20 bench of such retorts of a structure wherein the formation of the blocks composing the cross walls will also form the retort chambers themselves, and said retorts thus become integral parts of the complete bench 25 structure. By such a construction a bench of retorts is provided wherein all its parts, being composed of like materials, will be subject to like influences by the conditions under which the apparatus is operated, and 30 the difficulties incident to constructions heretofore in common use, as above described, will be obviated, all as will be hereinafter more fully described and claimed.

Referring to the accompanying drawings, 35 which are made a part hereof and on which similar reference characters indicate similar parts, Figure 1 is a longitudinal vertical section through a portion of a bench of gas retorts embodying my said invention; Fig. 2, 40 a vertical section on the line II—II in Fig. 1; Fig. 3, a vertical cross section on the line III—III in Fig. 1; and Fig. 4, a perspective detail showing a portion of two retorts illustrating the shape of the blocks composing 45 the cross walls and said retorts and the manner in which said blocks are assembled to form the structure.

In said drawings, the portions marked 1 indicate the main bench structure, 2 the retort 50 chambers, 3 the cross vertical walls comprising the interior of the bench structure, 4 the spaces between the walls 3, 5 a vertical side, 6 an opening leading from the combustion chamber of the furnace and

communicating with the vertical spaces between the cross walls of the bench structure, 55 7 an intermediate wall between different divisions of the retort structure, 8 the blocks of various forms comprising the cross walls and formed with projecting flanges 9 on one side. Said blocks are composed of appropriate refractory material and the general structure of the apparatus, aside from the bench of retorts, is or may be of any appropriate or approved character. As 60 65 most clearly illustrated in Fig. 4, each of said blocks is formed smooth on one side and with a flange projecting outwardly on its opposite side and adjacent to its inner edge, the several blocks being so formed 70 that when set together in the structure they will form a retort 2 of the desired shape in cross-section such as the arched top and flat bottom illustrated, or any other preferred form. The flanges surrounding each block 75 are so arranged as to join end to end, the flange on one block joining the flanges on the blocks on each side thereof, forming a complete flange around each retort chamber 2. The flanges of one cross wall abut 80 against the faces of the adjacent cross wall, thus forming retort chambers 2 extending from end to end of the structure, which may be thus made of any length desired. The flanges 9 project a sufficient distance so 85 that narrow free spaces 10 are provided between the adjacent cross walls for the circulation of the products of combustion coming into the bench from the combustion chamber, which spaces are completely bridged 90 over around each retort chamber by said flanges.

Referring particularly to Fig. 3, it will be noted that the blocks 11 and 12 overlap the key blocks of the arch, i. e., the blocks 95 respectively forming the top and bottom of the adjacent retorts. By means of this construction, the whole structure is interlocked, and it is especially advantageous in resisting a considerable amount of pressure 100 from the interior of the retorts that is liable to occur in discharging the coke. As will be seen, the bench of retorts is formed of what may be termed units arranged successively in the direction of length of the 105 retorts, each unit comprising the blocks which form the setting or partition walls and the flanges which intersect or bridge

the spaces between these transverse walls, these bridging flanges with the blocks forming the walls of the retort. As a result, these spaces provide relatively narrow channels each of which forms a channel for the circulation of the products of combustion. Furthermore, it will be seen that each unit is practically composed of spaced columns of superposed blocks, these columns being connected by arch structures at spaced apart points of the setting, these arch structures practically defining the upper and lower walls of a retort, the result being that the weight of a retort is placed substantially on these columns of superposed blocks and thus tends to restrict the effect of the weights of the individual retorts to points other than the retorts which may be located therebelow. As will be obvious, the blocks provide vertically spaced retort openings as well as a structure in which a block forms an element both in the setting and the retort wall.

This construction of retorts not only forms a structure which is for all practical purposes an integral mass of refractory material of uniform character and susceptible to uniform influences under the conditions surrounding the operation of the apparatus. Such a construction not only is of decided advantage for the reasons above indicated, but for the further reason that when so arranged the mass of refractory material is capable of the highest efficiency in transferring heat from the products of combustion to the coal in the retorts, but this feature is the subject matter of a companion application filed herewith and will not be further elaborated herein.

40 With the construction shown and above described, any holes that may be formed in the retorts can be readily patched while the retorts are in operation and without the necessity of putting the retorts out of commission for the purpose of making repairs, as was necessary under constructions of the prior art.

What I claim is:—

1. A bench of gas retorts formed of a series of cross walls spaced apart but set in near relation to each other, said cross walls being formed of appropriately-shaped blocks of refractory material and shaped to provide retort chambers extending from end to end of the bench, said blocks having projecting flanges forming each retort chamber and bridging the spaces between said cross walls, substantially as set forth.

60 2. A gas retort composed of a series of cross walls set near together, each wall being provided with a flange or rib forming the retort chamber and bridging the space between said walls, substantially as set forth.

65 3. A gas retort structure wherein the re-

tort chamber consists of sections of cross walls set with a space between them, each cross wall having a flange forming the retort chamber and bridging the space between said walls.

4. In a retort structure, cross walls composed of blocks of appropriate shapes fitted together and formed to provide a retort chamber, said blocks being each formed with a projecting flange adapted to fit with the flanges of the other blocks to form a flange completely forming each retort chamber, substantially as set forth.

5. In a retort structure having transverse spaced apart setting walls, a block forming part of a setting wall and having a projecting flange adapted to bridge the space between adjacent transverse walls, said block forming a portion of the retort wall.

6. A retort structure wherein an arched retort chamber consists of sections of cross walls set with a space between them, each cross wall having a block overlapping the arch forming the retort chamber.

7. In a retort or oven structure including two arched superposed retorts or ovens having the blocks forming the arch of one retort or oven overlapped or interlocked with blocks entering into the construction of the other retort or oven.

8. A bench of gas retorts composed of appropriately shaped blocks of refractory material, each block comprising a flanged portion entering into the formation of a retort and a web portion entering into the formation of partitions, whereby when assembled narrow passages are formed for the circulation of heating gases.

9. In a bench of gas retorts, units of refractory material adapted to be assembled in the direction of length of a retort and to form the retort and its setting in such assembled condition, adjacent assembled units forming a channel or passageway for the circulation of products of combustion.

10. In a bench of gas retorts, units of refractory material adapted to be assembled in the direction of length of a retort and to form the retort and its setting in such assembled condition, said assembled units forming parallel channels or passageways for the circulation of products of combustion.

11. In a bench of gas retorts, units of refractory material adapted to be assembled in the direction of length of a retort and to form the retort and its setting in such assembled condition, said assembled units forming relatively narrow parallel channels or passageways for the circulation of products of combustion, individual units forming walls for adjacent channels.

12. In a bench of retorts, an assemblage of units of refractory material, each unit forming an element both in a retort and a

retort support, a retort embodying portions of a plurality of assembled units.

13. In a bench of retorts, an assemblage of units of refractory material, each unit forming an element both in a retort and a retort support, a retort embodying portions of a plurality of assembled units, adjacent units on a horizontal plane forming opposing walls of a channel for the circulation of products of combustion.

14. In a bench of retort, an assemblage of units of refractory material, each unit forming an element both in a retort and a retort support, a retort embodying portions of a plurality of assembled units, adjacent units on a horizontal plane forming opposing walls of a channel for the circulation of products of combustion, the retort-forming portion of one of the units forming a connecting wall intersecting the channel.

15. In a bench of gas retorts, a setting comprising spaced columns of superposed blocks, and arch structures connecting blocks at spaced apart points of the setting, said arch structures being also formed of blocks, said columns and arch structures providing vertically spaced retort walls and openings.

16. In a bench of gas retorts, a setting comprising spaced columns of superposed blocks, and arch structures connecting blocks at spaced apart points of the setting, said arch structures being also formed of blocks, said blocks forming elements both in

the construction of the retort and a retort support.

17. In a bench of horizontal retorts, a bench and retort structure comprising a plurality of units arranged successively in the direction of length of the retorts, each unit corresponding to a transverse section of such structure.

18. A bench of retorts comprising a plurality of units arranged successively in the direction of length of the retort, each unit forming a transverse wall extending on planes intersecting the direction of length of the retort at substantially right angles and a portion of the retort walls.

19. A bench of retorts comprising a plurality of units arranged successively in the direction of length of the retort, each unit forming a transverse wall extending on planes intersecting the direction of length of the retort at substantially right angles and a portion of the retorts walls, the transverse walls of adjacent units being spaced apart, with the retort wall portion of a unit bridging the space between the walls, whereby a pair of units will provide a channel for the circulation of products of combustion.

In testimony whereof I affix my signature in presence of two witnesses.
